UNITED STATES PATENT OFFICE

2,691,469

DEVICE FOR WINDING DECORATIVE RIBBON INTO HANKS

June F. Willig and Ellen K. McGee,
St. Paul, Minn.

Application December 21, 1950, Serial No. 202,048

1 Claim. (Cl. 223—46)

1

This invention relates to the art of "gift-wrapping" packages and provides a novel device whereby the decorative pompon bows customarily used on gift packages may be easily and quickly fabricated by a housewife or other person who has had little or no previous experience in making such bows.

In recent years the "gift-wrapping" of packages has become a highly commercialized business. Various manufacturers have placed many new and attractive wrapping papers, decorative ribbons and the like on the market, and the various women's magazines very frequently feature articles promoting these new materials and new techniques for their use. One of the basic techniques which has been promoted, and which is now used in almost all gift wrapping of packages, is the ornamental pompon bow, fashioned from many loops of decorative ribbon to resemble a tufted ball. Such pompon bows are often illustrated in magazine articles of the type above referred to, the housewife then being given directions for making them. Unfortunately, however, it has heretofore been very difficult for a person, who only infrequently has occasion to do gift wrapping and thus has no particular skill in such procedure, to make up a bow which even approaches the illustrated bows in symmetry and general attractiveness.

One of the preliminary steps in making such bows is to wind a suitable length of decorative ribbon into a hank or coil. This hank or coil is then tied around its center and the end loops thereof are pulled apart and arranged to give a ball-like or generally spheroidal effect to the finished bow. It is very important in the fabrication of these bows that the hank be of suitable length for the package on which it is to be used and that the loops of the hank, after it is tied as above described, be of substantially equal length, so that when spread apart they will give the desired spheroidal effect.

Heretofore, people wrapping gifts, for lack of any device for the purpose, have customarily wound such hanks about any object close at hand, with the result that the coil is more likely than not to be of improper size for the desired purpose. Further, the wound hank is not easily removable from the object about which it has been wound. To overcome this latter difficulty, many housewives have attempted to wind the ribbon about their fingers. However, this method usually results in the loops of the hank becoming uneven when the ribbon is removed from the hand preparatory to tying, and is unsatisfactory for

2

that reason. Furthermore, it is difficult to keep the hank the desired length when it is wrapped about the fingers.

It is an object of this invention to provide a device

1. Whereby any individual can quickly wind hanks of various widths of ribbon for making decorative bows;
2. Which is adjustable so that different length hanks, as desired, may be wound upon it;
3. Which is very simple mechanically so that it can be easily used and adjusted by the individual;
4. Which can be produced at a cost low enough to warrant its sale at a low figure or its distribution free with the purchase of a quantity of ribbon.

Other objects and advantages of the instant invention will be apparent from the following detailed description and from the accompanying drawing, in which

Figure 1 is a side elevational view of the device in assembled form

Figure 2 is a plan view of the device in assembled form

Figure 3 is a cross-sectional view along the line 3—3 in Figure 1

Figure 4 is a cross-sectional view along the line 4—4 in Figure 1

Figure 5 is a cross-sectional view along the line 5—5 in Figure 1

Referring now in greater detail to the drawings, the preferred embodiment of the device of the instant invention, as illustrated, comprises a straight member 2 and a generally L-shaped member indicated by the reference character 3. For convenience of description, the base of said member 3 is designated 3a and the longer arm thereof is designated 3b. One end portion of member 2 is of substantially greater thickness than arm 3b and is provided at said thicker end with slot 4 extending transversely of the width of member 2. Said slot 4 is of a size which will snugly accommodate arm 3b, and, in assembly, said arm 3b is inserted within said slot, to form the assembled device shown in Figure 1. The portion of base 3a and of member 2 extending upwardly from arm 3b then provide supporting arms about which a strip of decorative ribbon may be wound into a hank. Member 2, when in position perpendicular to arm 3b, is freely slidable along the length thereof, to provide for varying of the distance between member 2 and base 3a so that hanks of different lengths may be wound. However, when a hank is actually

being wound about the ends of base 3a and member 2, the tension of the ribbon on member 2 will tip it slightly off the perpendicular, toward base 3a, with the result that arm 2 will "lock" in place by reason of the frictional contact between the edges of member 3b and the portions of arm 2 forming the top and bottom of slot 4. Arm 2 will not slide toward arm 3a, therefore, when a hank is being wound.

Stamped upon the outward face of arm 3b, 10 and recessed very slightly from the surface thereof, is a series of numbers 5, spaced an inch apart and 2, 3, 4, etc., inches from the outwardly facing edge of arm 3a. Said numbers provide means for "setting" the device so that a hank of the desired length may be wound. The section of member 2 overlying said numbers 5, when the device is assembled, may be provided with window 6 so that numbers 5 will be visible and member 2 may thus be accurately adjusted to 20 the desired distance from base 3a.

Members 2 and 3, comprising the device of this invention, may be made of any sturdy, relatively inflexible material such as sheet metal, wood, Celluloid, or even heavy weight cardboard. However, for convenience of manufacture, combined with low cost and attractive appearance, we prefer to manufacture the device from plastic material.

Arm 3b is preferably channeled along its length and ends, as indicated by the reference character 1, to provide the desirable rigidity in the member without materially increasing its weight, or the quantity of plastic material required for its manufacture.

Arm 3a and member 2 should desirably be at least three inches in length so that they will accommodate ribbon up to about 2½ inches wide even though it is only infrequently that ribbon that wide is made into bows. Arm 3b should be 40 sufficiently long to permit the winding of a hank 7 inches in length. Of course these dimensions are merely preferred and may be changed without departing from the spirit of our invention.

The particular styling of the device, as shown, for instance the shaping and tapering outer edges of arm 3a and member 2 are useful in reducing the amount of plastic material used in the manufacture of the device as well as in giving it a desirable "modern" appearance but it will of course be obvious that the styling of the device could be changed so that it might have quite a different appearance without departing from the principle thereof. Such style modifications should be understood to be within the scope and 50

spirit of this invention. It will of course be understood that the device of this invention is suitable for use in winding strip material other than decorative ribbon into hanks; for example, 5 it is adapted for winding string or yarn into hanks for use in making shag rugs, or for making yarn pompons.

It is believed that the operation and use of this invention has been fully described and disclosed in the foregoing description. Having thus described the invention and illustrated its use what we claim is:

A device for winding decorative ribbon into hanks for conversion into ornamental bows, comprising a rigid L-shaped member and a rigid straight member, the longer arm of said L-shaped member being channeled to provide a flange along each longitudinal edge thereof, the shorter arm of said L-shaped member tapering in width as it extends away from said longer arm and also tapering in thickness from its inner longitudinal edge to its outer longitudinal edge, one end of said straight member being provided with a flat ring, the longer arm of said L-shaped member being inserted through said ring, and being freely slideable therein, one face of said ring being provided with an aperture through which the surface of said longer arm will be visible, said surface carrying numerical designations of measurement, said straight member tapering in width from its apertured end toward its other end, and also tapering in thickness from its inner longitudinal edge toward its outer longitudinal edge, the longer arm of said L-shaped member being provided with protuberances spaced apart in accordance with said numerical designation of measurement, the inner surface of said flat ring engaging said protuberances to hold said straight member in any desired fixed position on the longer arm of said L-shaped member, the shorter arm of said L-shaped member and said straight member providing supports for the winding of a hank of ribbon.
